UNITED STATES PATENT OFFICE.

ERASTUS E. WINKLEY, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR OPERATING ON HEEL-LIFTS OR THE LIKE.

1,393,062.

Specification of Letters Patent. Patented Oct. 11, 1921.

Application filed December 29, 1915. Serial No. 69,207.

To all whom it may concern:

Be it known that I, ERASTUS E. WINKLEY, a citizen of the United States, residing at Lynn, in the county of Essex and State of Massachusetts, have invented certain new and useful Improvements in Machines for Operating on Heel-Lifts or the like; and I do hereby declare the following to be a full, clear, and exact description of the invention, such as will enable others skilled in the art to which it appertains to make and use the same.

This invention relates to machines for operating on blanks of sheet material such as the parts of shoe bottoms, and will be herein disclosed as embodied in a machine for operating on the lifts from which the heel of a shoe is made.

According to one method of building heels, a number of lifts or blanks of leather, leatherboard, or other material from which the heel is to be made, cut to the required size and shape, are adhesively secured together one on top of the other until a heel is built up which will be of the required thickness when compressed. The heel is then condensed or compressed in a heel compressing machine, leaving it in the condition in which it is attached to the shoe. In order to prepare the lifts for assembling to form a heel in this manner it is obviously desirable that each lift shall be of substantially uniform thickness throughout its area, although adjacent lifts may differ in thickness from each other. A very large percentage of heels are made from the cheaper and very inferior grades of leather, and this stock is very uneven and bumpy, often consisting of skivings, or of pieces of the cheap grades of split leather. Consequently, it is necessary to skive these lifts or operate upon them in some manner designed to reduce them to a substantially uniform thickness. The present invention is concerned particularly with the treatment of heel lifts which is desirable to prepare them for assembling in a heel.

The general object of the invention is to devise a machine which will perform the required operations on the lifts or like articles and arrange them conveniently for removal from the machine. It is proposed to make the machine entirely automatic in its action so that it will be necessary merely for an attendant to supply the machine with the

lifts and to take them away after they have been operated upon, although many of the features of the invention are applicable to machines which are not automatic to this extent.

In order to render the feeding of the lifts automatic, the blank feeding mechanism similar to that disclosed in my co-pending application Serial No. 18,494, filed April 1, 1915, Patent No. 1,251,852, dated January 1, 1918, may conveniently be employed. This mechanism is designed to insure the feeding of one lift or blank only at a time and has been found to operate very satisfactorily in the feeding of blanks having any substantial degree of stiffness or rigidity. But, as just stated, the stock from which heel lifts are made often is relatively flimsy; and accordingly, it is an important object of this invention to further improve the feeding mechanism of my earlier application with a view particularly to enabling this mechanism to handle satisfactorily blanks of stock which are comparatively flexible.

The invention also aims to devise means for interrupting automatically the normal operation of the machine under predetermined conditions, as for instance, when a lift becomes stuck in the machine, or upon the failure of the attendant to keep the machine supplied with lifts; a novel construction of skiving mechanism designed to handle lifts varying widely in dimensions and to afford convenient access to the path followed by the lifts, so that this path may be readily cleared in case a lift accidentally becomes lodged in the mechanism; and to provide simple and reliable means for taking the lifts away from the skiving mechanism and stacking them.

The manner in which it is proposed to accomplish these objects and the various features of the invention, including certain combinations and arrangements of parts, will be readily understood from the following description of the invention as embodied in a machine designed to skive or even heel lifts and similar blanks of sheet material. Referring now to the drawings,

Figure 1 is a plan view of a machine illustrating this embodiment of the invention;

Fig. 17 is a rear elevation of the magazine into which the lifts are delivered by the 35 machine;

Fig. 18 is a side elevation of part of the construction shown in Fig. 17;

Fig. 19 is a skeleton perspective view showing the mechanism that automatically stops 40 the machine under certain conditions;

Fig. 20 is a plan view of certain parts of the mechanism shown in Fig. 19; and

Fig. 21 is a cross sectional view on the line 21—21, Fig. 7.

45 Briefly stated, the machine shown comprises a skiving mechanism; a feeding mechanism designed to take lifts from a magazine and feed them automatically to said skiving mechanism, and including means for insuring the feeding of one lift only at a time; a transferring mechanism that carries the lifts away from the skiving mechanism and stacks them in a magazine; mechanism that operates automatically to stop the machine upon its failure to deliver lifts in a predetermined manner; and adjusting means arranged to enable the machine to operate on lifts varying widely in dimensions.

50 Referring now particularly to Figs. 1 to 4, the skiving mechanism shown is of the general type commonly used in the manufacture of boots and shoes to skive, split or even blanks of leather, and comprises two rolls 2 and 3 arranged one above the other, and a stationary knife 4 projecting between said

rolls. The periphery of the lower roll is roughened, as clearly shown in Fig. 3, to facilitate the feeding of the lifts, and the edge of the knife 4 is positioned very close to the periphery of this roll.

70

The lifts to be operated upon are placed in an inclined magazine 5 which consists of a front wall or plate 6, against which the breast ends of the lifts bear, and which is secured to the fixed parts of the machine 75 frame; and a V-shaped rear wall 7 carried by a bracket 8 which is mounted on a horizontal supporting plate or table 9 forming part of the machine frame. This bracket is adjustable toward and from the plate 6 to 80 enable the magazine to accommodate lifts differing in size; and it is secured in any adjusted position by a bolt 10 extending through a slot formed in the bracket and threaded into the plate or support 9, as 85 shown in Fig. 3. The lifts in the magazine 5 rest on the plate 9, the walls 6 and 7 merely serving as lateral supports for the lifts; and the wall 6 terminates just above the surface of the supporting plate 9, leaving an opening between the lower edge of this wall and the support 9 of a height sufficient to allow the thickest lift to be expelled through this opening. A weight 12, 90

slidable in the magazine, bears on the stack 95 of lifts positioned in it and presses them against the support 9. This weight carries a metal strap 13 the ends of which embrace the opposite edges of the wall 7 of the magazine and serve as guides for the weight. As 100 shown in Figs. 2, 4 and 7, the magazine also includes two side pieces 18 that rest on the support 9 and flare outwardly at their upper ends, as best shown in Fig. 2, so that they serve to guide the opposite side edges of the 105 lifts as they settle in the magazine and support them against lateral displacement. These two side pieces are mounted on a bolt 18', supported rotatively in the frame of the 110 machine and provided with a knurled handle 27 that has right and left hand threaded portions on which the two side pieces 18 are, respectively, supported. Consequently, by turning the hand piece 27 the side pieces 18 may be moved toward or from each other to 115 adjust them for lifts of different widths. A check nut 27', mounted on the bolt 18' adjacent to the handle 27, serves to clamp this bolt against accidental movement.

The lifts are fed out of the bottom of the 120 magazine one at a time to the skiving mechanism by means of a reciprocating feeder 14 (see Figs. 3 and 8) which is pivoted on a slide 15 and has a notched forward end shaped to engage the rear end and the bottom face of the lowermost lift in the stack. The forward end of this feeder also is forked and its two portions thus formed project through slots 11, Fig. 7, in the supporting plate 9. The slide 15 is reciprocated 125

130

back and forth on a guide rod 16, thus causing the feeder 14 on its forward stroke to push the lowermost lift out of the magazine and carry it to the rolls 2 and 3. On 5 its return stroke the feeder is depressed by its engagement with the lift then at the bottom of the stack and slides back under the stack. A spring 17 acts on the feeder 14 in a direction to press its forward or 10 lift engaging end upwardly, this movement being limited by the engagement of the tail of the feeder with a part of the slide 15, as clearly shown in Fig. 3. The mechanism for reciprocating the slide 15 comprises a 15 link 19 pivoted at its upper end to the slide 15 and at its lower end to an arm 20 which is pivoted on a stationary lever shaft 21. The upper end of the link 19 is forked and has a block 22 pivoted 20 between its arms which is adjustably secured by thumb nuts 23 and 24 to the threaded part 25 of a link which is pivoted to the upper end of a lever 26. This lever is fulcrumed on the lever shaft 25 21 and carries at its lower end a roll 28 that runs on the inner cam surface of a cam 29, mounted fast on the main shaft 30 of the machine. This shaft is constantly rotated while the machine is in operation. 30 The cam 29 operates through the connections just described to give the feeder 14 its return stroke, and a strong spring 31, having its ends secured, respectively, to the machine frame and the lower arm of the 35 lever 26, tends to hold the roll 28 in contact with the cam 29 and give the feeder 14 its forward or feeding stroke. The nuts 23 and 24 may be adjusted along the threaded part of the link 25, carrying the block 22 40 with them, and thus adjusting the limits of the stroke of the feeder 14 toward or from the skiving mechanism. This adjustment obviously is desirable to facilitate the feeding of lifts of different lengths. 45 The feeding mechanism so far described is substantially like that disclosed in my United States patent above identified. This mechanism also includes a stop similar to that disclosed in said application, which insures the feeding of one lift only at a time. 50 That is, there is a tendency for the second lift from the bottom of the stack to feed ahead with the first lift, due to the friction existing between these two lifts, and this 55 stop is positioned directly in front of the bottom of the stack and is so constructed as to distinguish between the first and second lift and to permit the first lift to be advanced by the feeder 14 but prevents the 60 other lifts from being fed forward at the same time.

This stop comprises a forked member 32 (see Figs. 9 and 13) which, since it feels for the second lift, may be termed a "finger," and a presser foot 34 that slides in

the slot between the two parts of the member 32 but is thicker than said member so that it projects in front of and behind it. The shanks of the two members 32 and 34 lie side by side in a vertical holder 35 in 70 which they are movable, independently of each other, in directions toward and from the support 9 on which the stack of lifts rests. This holder is pivoted on a rod 36 so that the members 32 and 34 may move together toward and from the magazine 5. The finger 32 is pressed downwardly toward the support 9 by a spring 37, which abuts at its upper end against an overhanging extension 38 of the holder 35, and bears at its lower end on a collar 39 pinned to a rod 40 which is secured to a lug 41 that projects rigidly from the upper portion of the member 32. The presser foot 34 likewise is normally urged toward the support 9 by a spring 42, secured at one end to a pin projecting from the holder 35 and at its opposite end to a lug 44 projecting from the upper part of the presser foot 34. The lugs 41 and 44 both project through slots 80 formed for them in the opposite walls of the holder 35. 90

A cam mechanism is provided to control the movements of both the finger and the presser foot and is operative to raise one of these members while the other is lowered. This mechanism (as best shown in Figs. 3, 8 and 13) comprises a sleeve 45, mounted to rock on the rod 36, and carrying at one side of said rod a pair of lugs 46 that straddle the rod 40 and are adapted to bear on the lower end of the collar 39, and provided at the opposite side of the rod 36 with an arm carrying a pin 48 that is positioned in a slot 49 formed in the upper end of a link 50, the lower end 100 of which is pivoted to the lug 44 that projects from the presser foot. In the position in which the parts are shown in Fig. 8, the pin 48 acts through the link 50 to hold the presser foot 34 at the upper limit of its 110 stroke in the holder 35; and the spring 37 at this time holds the finger 32 against the support 9. If, however, the sleeve 45 were rocked in a clockwise direction, the lugs 46 would engage the lower surface of the block 39 and operate through the rod 40 and lug 41 to raise the finger 32, the pin 48 at the same time moving downwardly and permitting the spring 42 to depress the presser foot 34. In order to effect the required 120 rocking movements of the sleeve 45, it is connected by an adjustable link 52, Fig. 3, with one arm of a bell crank lever 53 which is fulcrumed on the lever shaft 21 and has mounted on its opposite arm a roll 54 that 125 runs on the surface of a cam 55 mounted fast on the main shaft 30. A spring 56 operates on the lever 53 to hold the roll 54 against the periphery of the cam 55. 130

which is effective to carry the finger 32 and presser foot 34 together toward and from the stack of lifts in the magazine 5, is produced by means of an arm 58 projecting from the holder 35, and a link 59 (see Figs. 2 and 4) connecting said arm with one arm of a bell crank lever 60, which is fulcrumed on the lever shaft 21 and carries, at the end of its other arm, a roll running on the inner cam surface of a cam 61 fast on the main shaft 30. A spring 62 acts on the lever 60 in a direction tending to hold the roll in contact with the cam face of the cam 61, so that the cam is operative through the connections just described to swing the holder 35 away from the magazine 5 and the spring 62 swings the holder 35 toward the magazine 5.

The operating mechanisms above described are so timed with reference to each other that the finger 32 is pressed downwardly into contact with the support 9 when the feeder 14 starts ahead, carrying the first lift in the magazine from the position in which it is shown in Fig. 8 to that in which it is shown in Fig. 9, where the forward edge or breast of the lift comes in contact with the finger 32. The feeder 14 pauses at this time in its stroke but moves far enough to cause the first lift to swing the finger 32 and consequently the holder 35 somewhat away from the magazine 5, this swinging movement being resisted by the spring 62. The presser foot 34 next advances toward the support 9 into contact with the forward margin of the first lift and presses this part of the lift firmly against the support. If the second lift has been dragged forward by the first lift, the movement of the presser foot 34 may be arrested by its contact with the margin of the second lift, but in either event this presser foot acts to force the margin of the first lift, adjacent to the point of engagement therewith of the finger 32, firmly against the support 9. The parts are now in substantially the positions in which they are shown in Fig. 10. The finger 32 now rises and its end moves across the forward edge of the first lift away from the support 9 and toward the other lifts in the stack. During this movement, the spring 62 keeps pressing the finger 32 firmly against the edge of the first lift with sufficient force to move this lift backwardly if it were not backed up by the feeder 14. Consequently as soon as the end of the finger is retracted far enough to carry it out of contact with the forward edge of the first lift, the force of the spring 62 swings the finger 32 and presser foot 34 sharply toward the magazine 5, moving the finger into the angular space between the margin of the first lift and the forward edge of the second lift. If the presser foot 34 is resting on the margin of the first lift at this time, as shown in Fig. 10, it will engage the forward edge of the second

lift and kick it backwardly; but if the presser foot is bearing on the second lift, the finger 32 will engage the edge of the second lift and force it back. The upward or retractive movement of the finger 32 is of sufficient extent to insure the movement of this finger out of engagement with the edge of the thickest lift, the presser foot 34 in the meantime maintaining its contact with the first lift, as shown in Fig. 11. The positions of these two stop members are then quickly reversed. That is, the finger 32 is advanced from the position in which it appears in Fig. 11 until it comes in contact with the upper face of the first lift; and the presser foot 34 is withdrawn, the parts shifting from the positions in which they are shown in Fig. 11 to those shown in Fig. 12. The forward stroke of the feeder 14 may be resumed as soon as the finger 32 has moved out of engagement with the forward edge of the first lift; but preferably this movement is so timed as to allow the reversal of the finger and presser foot to be completed before the drag of the first lift on the second lift is sufficient to carry the second lift beyond the plane of the rear face of the finger, in case the presser foot happens to be resting on the second lift at this time. Of course if the presser foot is resting on the first lift, it will retain the second lift. This timing of the movements of the parts enables the finger 32 to move down into the position in which it is shown in Fig. 12, and bear yieldingly on the upper face of the first lift, where it is effective to retain the second lift or limit the forward movement of it. As soon as the feeder 14 carries the first lift out from under the finger 32, the spring 37 forces this finger down into contact with the support 9, as shown in Fig. 8, and it remains in this position until the feeder 14 has withdrawn to the backward limit of its stroke and moved ahead again sufficiently to carry the lift then resting on the support 9 into contact with the finger 32, as shown in Fig. 9. While the stop is changing from the position in which it is shown in Fig. 12 to that shown in Fig. 9, the holder 35 is swung on its pivot to move the finger 32 away from the stack of lifts to allow them to settle and is then swung back again into the position shown in Fig. 9. The lift separating operation then is repeated by the stop members 32 and 34.

The present stop construction differs from that shown in my United States patent above identified in that in the earlier construction the two stop members lie one in front of the other. Accordingly, in effecting the separating movement of the lifts it is possible, with this construction, for the forward margin of a very flimsy lift to be dragged upwardly by its contact with the stop finger and curled around in front of

the forward edge of the second lift and thus prevent the desired lift separating action. The present construction, however, prevents any action of this kind since the presser foot 34 effectually resists any tendency of the margin of the first lift to follow or be dragged upwardly by the finger 32. In other words, the presser foot in the present construction prevents any displacement of the part of the margin of the first lift on which the stop operates, while the finger 32 moves across the forward edge of this lift and feels for the second lift, kicking this second lift backwardly as soon as it finds it.

It should also be understood that, while the inclined magazine construction shown in this machine is convenient because of the relative positions of the parts, it is not essential to the successful operation of this feeding mechanism, since obviously a vertical magazine could be used as well if an aperture through which to feed the lifts were provided at the bottom of the magazine of a sufficient height to permit the passage of the thickest lift that would be run through the machine. If two or more lifts were then advanced at the same time by the feeder 14, the separating mechanism would operate exactly as above described to insure the feeding of one lift only at each stroke of the feeder. When two lifts are accidentally advanced together, it is desirable to have room enough to allow the forward margin of the first lift to project in front of the second lift, or to allow the feeding mechanism to produce this relationship in the course of the separating operation; and this relationship may be obtained with either arrangement of magazine mentioned.

The lift separating operation now being completed, the feeder 14 carries the first lift under a presser plate 64 which is pivoted to a pair of ears projecting from the lower end of the front wall 6 of the magazine 5 (see Figs. 5 and 8). This plate serves to hold the lift firmly against the support 9 and prevents any tendency of it to buckle. Pressure is applied to this plate by a small plunger 65 (see Fig. 5) which is guided in a housing 66 secured to the forward end of the yoke that supports the upper roll 2, and is pressed downwardly by a spring 67 positioned in said housing. This pin carries a head that slides in the chamber for the spring 67, which is larger than the passage through which the pin itself slides, so that the head limits the downward movement of the pin. A plug threaded into the end of this chamber backs up the spring 67. The two magazine plates 18 also guide the lift laterally during its travel toward the skiving mechanism.

The stroke of the feeder 14 is sufficient to carry the forward edge of the lift into the grasp of the rolls 2 and 3 of the skiving mechanism. This mechanism resembles in its general organization that of the ordinary skiving, splitting or evening machine. The shaft 69, which carries the lower roll 3, is supported at the opposite ends of the roll in bearing blocks 68, Fig. 7, which are movable vertically in suitable guideways and are supported by stiff springs, one of which is indicated at 70 in Fig. 3. Stops 79, Fig. 7, limit the upward movement of the bearing blocks 68. Each spring is backed up by an adjustable bolt 71 threaded through a bracket 72 forming part of the machine frame so that the tension of the springs can be adjusted. The knife 4 (as shown in Fig. 3) rests on a suitable frame piece and is backed up by a pair of bolts 73 by means of which it can be adjusted toward and from the plane of the axes of the rolls 2 and 3. As shown in Fig. 7, the opposite ends of the knife 4 are beveled and are clamped under blocks 74 and 75, the latter block being readily removable to permit the removal of the knife. The shaft 76 of the upper roll 2 is journaled in a yoke 77 which swings on a pivot 78 mounted at one side of the plane of the rolls 2 and 3, so that the upper roll can be swung out of its operative relationship to the lower roll and the knife 4, into a position where it will afford free access to the path of travel of the lifts through the skiving mechanism; thus enabling an attendant to clear this path readily in case a lift becomes jammed in any part of this mechanism. Fig. 6 shows the bottom of this yoke and the parts carried thereby when tipped back into an inoperative position. The two rolls 2 and 3 are driven by independent gear connections (see Fig. 5) with a pinion 80 that rotates with a sprocket wheel 81 driven by a chain 82 which is driven by another sprocket wheel 83 fast on the main shaft 30. An idle sprocket wheel 84 (see Fig. 3) keeps this chain tight.

The upper roll 2 normally is locked in its operative position by means of a handle 110 which is adjustable to vary the operative relationship of the upper roll to the lower roll. This handle comprises a piece 86 pivoted to the yoke 77 (see Fig. 3) and a bolt 87 threaded into the member 86 and having pinned thereto a hand piece 88. A check nut 89, threaded on to the bolt 87, holds this member in an adjusted position in the member 86. Mounted loosely on the bolt 87 between suitable collars which are pinned thereto, is a sleeve 90 carrying a pair of lugs 91 that are arranged to lie under two shoulders 92 formed on a bracket that constitutes part of the machine frame. This sleeve is prevented from rotating by means of a pin 93 which is secured to it and extends through a lug projecting from the part 86. This handle normally is held in the position in which it is shown in Fig. 3, by a latch 125 which grasps the upper part of the bolt 87 130

adjacent to the hand piece 88, and consists of two arms 95 (see Figs. 1 and 3) mounted on a common pivot and pressed yieldingly together by a spring 96 (Fig. 1). When it is desired to swing the upper roll into its inoperative position, the hand piece 88 is grasped and swung about the pivot of the part 86 in a clockwise direction, as the parts are seen in Fig. 3, until the handle is released from the grasp of the latch 95; and the entire yoke 77 and the parts carried thereby are then swung upwardly about the axis of the pivot 78 into the position shown in dotted lines in Fig. 4.

When the upper roll is locked in its operative position, as shown in Fig. 3, the passage of a lift between the rolls 2 and 3 tends to separate the rolls more or less depending upon the thickness of the lift. The weight of the yoke and the parts carried thereby is so disposed with reference to the pivot 78, that it tends to force the roll 2 toward the roll 3; and this tendency is aided by a plunger 97 (see Fig. 4) mounted to slide in the holder 98 pivoted on the machine frame at 99 and pressed downwardly by a spring 100 contained in said holder 98. The downward movement of the roll 2 is limited by the engagement of a pin 94, Figs. 2 and 6, on the yoke with one of the bearing blocks 68. The plunger 97 bears on the yoke 77 at a point above the roll 2. The spring 100, however, has only a light tension as compared with that of the springs 70, so that, as soon as a lift enters between the rolls 2 and 3, it overcomes the weight of the parts carried by the yoke 77 and the spring 100 and lifts the roll 2 until the lugs 91 strike the parts 92 and prevent any further lifting movement. Thereafter the roll 2 operates as though it were mounted to revolve on a fixed axis; and the lift then depresses the roll 3 against the tension of the springs 70 to an extent depending upon its thickness and density. Since both rolls are positively driven in directions tending to feed the lift between them and against the edge of the knife 4, this knife will skive off the part of the lift that passes between it and the lower roll 3, and this part will drop through the machine as waste, the part of the lift which passes between the roll 2 and the knife being retained. By loosening the check nut 89 and turning the hand piece 88 to rotate the bolt 87, the lugs 91 can be moved toward or from the shoulders 92, thus adjusting the width of the space between the roll 2 and the edge of the knife 4 and varying the operative relationship of the upper roll to its companion roll and the knife. It is contemplated that the machine will be used to skive or even lifts which have been graded according to thickness or density and that, therefore, the upper roll can be set according to the thickness or density of the lot of lifts being operated upon. This arrangement of

the rolls is also of advantage in that it results in enabling them to press the stock firmly between them even in case they encounter a piece of stock much thinner than that for which they are set, and consequently insures the accurate feeding of the lifts through the skiving mechanism notwithstanding substantial changes in thickness or density of the lifts. If this mechanism is properly set, the lifts come through it "evened"; or each reduced to a uniform thickness throughout its area.

The end of the holder 98 is provided with a notch 102 (see Fig. 4) shaped to engage a tongue or projection 103 on the yoke 77 when this yoke is swung into its backward or inoperative position and to hold the yoke in this position.

Mechanism is provided which operates automatically to take the lifts away from the skiving mechanism after they have been operated upon and to stack them in a magazine. The lifts, as they are forced past the knife 4 by the grip of the rolls 2 and 3, travel on to a support 104 (see Figs. 5 and 7) each lift being urged along this support by the one behind it. The lifts are guided laterally during this movement between two side guiding members 105 and 106, respectively, (see Fig. 7). These members are grooved to sit on tongued frame pieces 107 and 108, respectively, and are secured adjustably thereto by bolts projecting through slots formed in these parts. This arrangement, as clearly shown in Fig. 7, enables the side guides to be adjusted toward and from each other to accommodate lifts varying in width. Pivoted to the respective guides 105 and 106 are additional guiding members 109 and 110, respectively, acted upon by springs 111 and 112 in directions tending to swing them toward each other and consequently tending to press them against the opposite sides of a lift as it travels between them along the support 104. These members 109 and 110 are so shaped that they not only engage the opposite edges of each lift but also overlie the opposite margins of the lift. At the ends of the parts 109 and 110 remote from the roll 3, these members have pivoted thereto additional guides 113 and 114, respectively, (see Figs. 7 and 21) which are shaped similarly to the parts 109 and 110 and partake of the swinging movement of the latter parts about their pivots. These two members 113 and 114, however, are mounted on horizontal pivots supported by the respective guides 109 and 110 so that their outer or free ends can swing upwardly away from the support 104. Coiled springs 115 and 116 act, respectively, on the guiding members 113 and 114 to hold them normally against the upper face of the support 104.

As each individual lift emerges from between the rolls 2 and 3 and begins to move

along the support 104 between the guides 105 and 106, it is pressed against the support 104 by a presser plate 119 (see Figs. 5 and 6). The forward end of this plate is pivoted between 5 two plates 120, mounted at opposite ends of the upper roll 2 and each loosely encircling the shaft 76 which carries said roll, so that they are free to move around the axis of said roll, carrying the end of the plate 119 with 10 them. This movement, of course, carries the plate toward or from the support 104 over which the lifts travel. The rear end portion of the plate 119 has pivoted thereto a rod 122, which extends loosely through a 15 plate 123 supported in the yoke 77, and is encircled by a spring that acts on the rod 122 to press the rear end of the plate 119 against the support 104. Another rod 124, similar to the rod 122 and similarly connected to the 20 parts 119 and 123, is acted upon by another coiled spring that presses the forward end of the plate toward the support 104. Consequently this device is operative to hold the lifts yieldingly against the plate 104 as they 25 travel over said plate in moving away from the skiving mechanism.

As the lifts travel along the supporting plate 104 in this manner, each lift pushing the one in advance of it, the forward lift 30 is brought into the range of action of a reciprocating pusher device 125 (Fig. 3) which is pivoted to the upper end of an arm 126 mounted fast on a rock shaft 127. This pusher, as shown in Fig. 7, is Y-shaped, its 35 shank being pivoted to the arm 126 and its two diverging ends being curved to project through slots 128 formed in the plate 104, where they are operative to bear against the back of a lift near its opposite 40 sides and push it along the support 104 away from the skiving mechanism. A leaf spring, shown in Fig. 3 acts on the pusher 125 to hold its lift engaging ends in the slots 128, but permits this member to be depressed on its return stroke by its engagement 45 with the bottom of a lift resting on the support 104. The presser device 119 and the overlapping margins of the guides 109 and 110 hold the lifts on the support 50 while they are being advanced by the pusher and resist any tendency of the pusher to raise the lifts off the support 104 as it travels backwardly under them. The two arms or pushing ends of the part 125 rise when they 55 arrive at the rear end of the forward lift, since they are so spaced apart as to enter the space between the opposite breast corners of one lift and the curved rear end of the next preceding lift.

60 This pusher 125 advances the lifts one at a time along the support 104 into the grasp of a rotary transferring device. Inasmuch as it is desirable to have the pusher deliver the lifts at a definite point, and since 65 it will have to carry lifts varying in length,

provision is made for adjusting the stroke of the pusher accordingly. The operating mechanism for this pusher includes an arm 129, Fig. 3, fast on the rock shaft 127, and a link 130 connecting the free end of this arm 70 with a block slideable in a slot 131 formed in a lever arm 132 pivoted on the lever shaft 21. Another arm 133, pivoted close beside the arm 132 on the shaft 21, carries a roll that runs on the periphery of a cam 134 fast 75 on the shaft 30. The two arms 132 and 133 are connected together rigidly but adjustably so that they act as a bell crank lever and transmit through the mechanism just described the motion of the cam 134 to the 80 pusher 125. For the purpose of connecting the two lever arms in this manner each arm is provided with a lug, and a bolt 135 is threaded into one of these lugs and extends loosely through the other and has fast there- 85 on a collar and a handle 137 which bear on opposite sides of the latter lug, so that as this bolt is turned it swings the two arms 132 and 133 toward or from each other. This adjustment obviously is effective to 90 transfer the limits of the stroke of the pusher 125 along the support 104 without changing the length of said stroke. A check nut 138, threaded on the bolt 135, serves to clamp the handle 137 in adjusted position. 95 In order to change the length of stroke of the pusher 125, another bolt 139, mounted for rotation in a lug carried by the arm 132, is threaded through the block that slides in the slot 131 and is provided with a handle 100 140 and a check nut 141 similar to the parts 138 and 137. By turning the bolt 139, the block carrying the lower pivot of the link 130 is moved along the slot 131 toward or from the pivot point of the arm 132, and 105 thus varies the throw of this block, and consequently the throw or length of stroke of the pusher 125. These adjustments enable an attendant to so modify the stroke of the pusher 125 that it will push a lift of 110 any ordinary size to a given point on the support 104.

The pusher 125 carries the lifts into the path of a transfferer consisting of a carrier member 144 on which are mounted three 115 pairs of grippers, each pair being operative to grasp a lift between them and transfer the lift from the support 104 to the magazine in which the lifts are stacked in convenient condition to be removed from the machine. A shaft 145, mounted in suitable bearings, supports the member 144; and is driven by gear connections with a shaft 146 on which is fixed a gear 147, which forms part of the driving means for the lower roll 3 and which 120 is driven by the gear 80 on the shaft 78. The carrier also includes an annular part 149 (see Fig. 15) which rotates on a stationary bracket 150 having a cylindrical bearing surface for the part 149.

125

130

130

Each pair of grippers consists of two members 152 and 154, and since the three pairs are alike in construction and mounting, a detailed description of one pair only is necessary. The grippers 152 are mounted respectively fast on rock shafts 155 (see Figs. 14 to 16) that are journaled in the carrier parts 144 and 149. A collar 156 is pinned on each shaft 155 and is positioned in a countersunk hole in the outer face of the part 149, as shown in Fig. 15; and an annular cam plate 157 is secured to the outer face of the part 149, as shown in Figs. 15 and 16, where it cooperates with the collar 156 to enable the shafts 155 to space the part 149 properly away from its cooperating carrier part 144. These shafts also compel the parts 149 and 157 to rotate with the shaft 145. Each gripper 152 thus is pivotally mounted in the rotating carrier; and in order to control its motion about its pivot each shaft 155 has pinned thereon a small rocker head 159, as best shown in Figs. 1, 14 and 15, which carries two cam rolls 160 and 161. One of these rolls projects farther from the rocker head than the other, as shown in Fig. 15, and they are designed to run in different cam ways or paths formed in a stationary cam 162 which is secured to the face of the bearing for the shaft 145. The carrier rotates in a clockwise direction, as the parts are seen in Fig. 14; and these cam ways are shaped to cause each gripper 152 to travel in such a path that its free end moves in the path indicated by the dotted line P, Fig. 14, and in the direction indicated by the arrows in said line. The other gripper 154 of each pair is pivoted on its companion gripper 152, as shown in Figs. 14 and 16, so that it partakes of the movements of the latter gripper but can also swing on it. Normally the grippers are held closed by a coiled spring 165. In order to open the grippers to enable them to grasp a lift, each of the grippers 154 is provided with a tail piece 166; and as each pair of grippers swing toward the position in which the lower left hand pair is shown in Fig. 14, the tail piece 166 is swung up into contact with a pin 170 that projects through the stationary bearing member 150. The rotative movement of the carrier, while the tail piece 166 remains in contact with the pin 170, swings the gripper 154 about its pivot into an open position with reference to its companion gripper 152, the latter gripper in the meantime being swung, by the engagement of the roll 160 with the cam 162, into a position substantially parallel with the upper face of the support 104, as shown in Fig. 14. While this pair of grippers is thus held open, the pusher 125 advances a lift along the support 104 into their grasp; and as soon as the pusher 125 has

completed its delivering movement, the pin 170 is moved longitudinally to withdraw it from contact with the tail piece 166, thus allowing the spring 165 to snap the gripper 154 down into contact with the lift and clamp it against the gripper 152. In order to produce this withdrawing movement of the pin 170, this pin has fixed thereto a small bracket 171, Fig. 16, which is guided on a stud 172 secured in the bearing piece 150 adjacent to said end, and this bracket carries a roll 173 that runs on the face of the cam 157 which rotates with the carrier part 149. A spring 174 acts on the bracket 171 to press it and the pin 170 inwardly into the path of the tail pieces 166. The rotative movement of the carrier also tends to swing the tail piece 166 out of engagement with the pin 170. A thin band or guard 176 (see Fig. 14) partly encircles the transerrer and prevents the accidental entry of a lift into the interior of the transerrer.

As soon as a lift has been grasped by a pair of grippers the rotative movement of the carrier 144 causes the grippers to raise the lift off the support 104 and transfer it bodily. The two guide members 113 and 114 overlie the opposite marginal portions of the lift as it rests on the support 104; and the outer ends of these guide pieces are, by their engagement with the lift, swung upwardly about their pivots against the tension of the springs 115 and 116, respectively, until the lift has been carried far enough to move it out of engagement with these members, when their springs return them again into their normal positions in contact with the support 104.

Further rotative movement of the carrier 144 effects the transfer of the lift held between the grippers to a horizontal receiving magazine 178 which comprises two L-shaped members facing each other, as shown in Fig. 17. The grippers swing the lift which they carry into the open end of this magazine and behind a yieldable latch or pawl 180 which retains them in the magazine. As indicated in Fig. 15, the guard 176 is slotted to permit the fingers of the grippers 152 and 154 to project therethrough and, as shown in Fig. 14, the upper end of this guard rests on a stationary bracket 163, constituting a portion of the bottom wall of the magazine, which is similarly slotted and is provided on its upper surface with a shoulder 164. As a pair of grippers carry a lift into the open end of the magazine, the breast edge of the lift rides over the upper end of the guard and into the notch behind the shoulder 164. The entrance of the lift into this notch is facilitated by the peculiar retiring movement of the grippers which, as indicated in Fig. 14, is directly downward from the shoulder 164. That is, each pair of gri-

pers swings a lift into the open end of the magazine, crowding back the other lifts already in it, and then retires, pulling the lift into the notch behind the shoulder 164 and 5 sliding off the lift during its retiring movement. It is thus unnecessary to open the grippers to release the lift. In this manner, the lifts are successively piled in stacked relation one against another in the magazine.

10 The two plates 178 constituting the receiving magazine are, as shown in Figs. 3, 17 and 18, supported on suitable stationary parts secured on the frame and these two 15 plates are adjustable toward and from each other. For the purpose of effecting this adjustment the members 178 are provided with depending lugs which enter, respectively, notches formed in the upper ends of 20 two arms 181 (see Fig. 17) pinned to rock shafts 183 that lie under and parallel to the parts 178. These rods carry intermeshing segments 184 and one of them has secured thereto an arm 186 which carries a clamping handle 188 extending through a slot 189 formed in a stationary bracket mounted on the machine frame. By moving this arm up or down, and turning the handle 188 to lock it in an adjusted position, the outer 25 ends of the arms 181 are swung toward or from each other, carrying with them the two parts 178 of the magazine and thus increasing or decreasing the width of the magazine. A similar pair of arms, one of which is indicated at 190, Fig. 3, is secured to the rods 30 183 near the forward end of the magazine so that both ends are adjusted at the same time. As best shown in Fig. 1, the forward side plates of the magazine consist of two 35 pieces 179, pivoted respectively to the two parts 178, and each held substantially in alinement with the members 178 by springs, one of which is indicated at 191. These parts 179 flare outwardly at their forward 40 ends to aid in guiding the lifts into the open end of the magazine; and the springs 191 allow these parts to yield under pressure of a lift and tend to center the lift in the magazine.

45 Broadly considered, the specific construction of the receiving magazine is immaterial, and any form of device or means for receiving and holding lifts or blanks in stacked relation may be employed.

50 As above stated, it is desirable to interrupt the normal operation of the machine under some conditions, as for instance when the supply of lifts in the magazine 5 has been exhausted or when for any reason a 55 lift has become stuck in the machine. In the present construction, this interruption of operation is effected by stopping the entire machine, although in some cases it may be desirable to stop the operation of a cer-

tain mechanism or mechanisms only. In 65 the arrangement shown a mechanism is provided which is controlled by the passage of lifts through the machine so that, when the machine is operating properly and the lifts are traveling through the machine in the 70 desired manner, the machine is maintained in operation; but upon the failure of the machine to deliver a lift at a predetermined point in each cycle of operations, the mechanism above referred to acts automatically 75 to throw the power off the machine and stop it. This mechanism is under the control of the latch or pawl 180 at the receiving end of the magazine 178.

Referring now particularly to Figs. 1, 2, 80 4 and 19, it will be seen that the main shaft 30 of the machine carries a loose pulley 193 and a fast pulley 194 and that a belt shipper 195, pivoted on the frame, is arranged to throw the belt 196 from either pulley to the 85 other. When the machine is in operation the belt of course is on the fast pulley 194 and the shipper 195 at this time is in the position in which it appears in Figs. 1, 2 and 19. A shipper rod 198 is arranged to bear 90 against the shipper 195 and is supported in suitable guides for longitudinal movement in a horizontal plane substantially parallel to the shaft 30. A spring 199 acts on this rod 198 in a direction tending to cause it to 95 throw the shipper to transfer the belt from the fast to the loose pulley and thus to stop the machine. The rod, however, is normally locked against movement under the influence of this spring by means of a latch 200 pivoted on the machine frame and having a tail piece, as shown in Fig. 19, lying in the path of a stop 201 fixed on the rod 198. A coiled spring acts on this latch 200 to hold it in 100 engagement with the stop 201. In order to 105 move the latch 200 to release the stop, a rod 203 (see Figs. 4 and 19) is supported in suitable guideways for longitudinal movement into and out of engagement with the upper end of this latch and is urged toward the 110 latch by a spring 204. Normally this rod is held out of engagement with the latch, by the engagement of a roll 206, which it carries, with the upper arm of a bell crank lever 205 fulcrumed on the shaft 21. The 115 lower arm of this lever carries a roll that runs on the surface of a cam 207 fast on the main shaft 30, a spring 208 acting on the lever to hold the roll against the cam. This cam is so designed that it holds the upper 120 arm of the bell crank lever backward during the greater part of each revolution of the shaft 30, which produces one cycle of operations of the machine. There is, however, a short low spot in the cam 207, as shown in 125 Figs. 4 and 19, which permits the rod 203 to move the bell crank lever 205 forward and to come into engagement with the latch 200

and trip it, thus stopping the operation of the machine. But normally another means becomes effective at this point to restrain the rod 203, and this means is controlled by the 5 latch or pawl 180. The rod 203 has a notch 209 cut in it at a point such that, when the rod is in the position in which it appears in Figs. 4 and 19, the notch lies in the path of a dog 210 pivoted on the frame at 211. A 10 spring 212 acts on this dog in a direction tending to hold it out of the notch 209. This dog is connected by a yielding link 213 to an arm 214 fast on the lower end of a vertical rock shaft 215 that carries, at its upper 15 end, a wing 216 against which bears a small cam piece 217 fast on a pivot 218 which supports the pawl 180.

It will now be evident that, when a pair of the grippers on the carrier 144 deliver a 20 lift to the receiving magazine 178, the contact of this lift with the forward end of the pawl 180 raises this pawl slightly, and causes the cam piece 217 to rock the shaft 215 in a direction such that the arm 214 and link 213 25 press the dog 210 into the notch 209, where it prevents the rod 203 from moving forward under the influence of the spring 204. This operation takes place at that point in the cycle of operations of the machine during 30 which the roll carried by the lever 205 is passing over the low spot in the cam 207. If for any reason the pawl 180 is not raised at this point in the cycle, the dog 210 will be held out of the notch 209 and the rod 203 35 will be pushed forward by the spring 204, tripping the latch 200 and allowing the spring 199 to throw the shipper 195 far enough to shift the belt on to the loose pulley 193 and stop the machine. If the difficulty which caused the stopping of the 40 machine is then removed and the shipper 195 is thrown back by hand, the rotation of the cam 207 produced by the application of power to the machine again will operate 45 through the bell crank lever 205 to throw the rod 203 back out of engagement with the latch 200, and will thus allow this latch to swing up in front of the stop 201 where it will again retain the belt shipper in its running 50 position. It will thus be evident that the member 180 serves not only the purpose of a pawl operative to retain the lifts in their proper positions in the magazine 178, but also performs the functions of a feeler, 55 since it feels for the lifts entering the magazine and allows the trip mechanism to operate or prevents it from operating depending upon whether or not it is engaged by a lift at the proper time.

60 The yielding link connecting the dog 210 and the arm 214 consists merely of two pieces pivoted, respectively, to these members and one telescoping within the other. A spring 219 tends to hold them apart and

the relative movement of these two parts 65 under the influence of this spring is limited by a pin 221. A torsion spring 227, Fig. 15, acts on the rock shaft 215 in a direction tending to hold the wing 216 against the cam 217.

The pivot 218, which carries the member 180, is supported in a plate 223 (see Figs. 1 and 4), which is pivoted on the top of a vertically adjustable plate 224, and has a curved slot formed therein through which a clamping screw 225 extends and serves to clamp the plate in an adjusted position. This swinging adjustment enables an attendant to move the pawl 180 into and out of its operative position. A clamping bolt 80 226 extends through a vertical slot in the plate 224, Fig. 4, and serves to clamp this plate in various positions of vertical adjustment. This adjustment is convenient in positioning the member 180 properly to engage lifts of different lengths.

The operations of the machine has been explained so completely in connection with the description given above of the construction and arrangement of the various parts 90 that any further description of operation is believed to be unnecessary.

While the invention has been herein disclosed as embodied in a machine designed to skive or even heel lifts, it is of course obvious that the invention is not limited in its application to this operation, nor to details of construction and operation herein disclosed, nor to the conjoint use of all its features, but that the various features of the 100 invention may be embodied either separately or collectively in various forms without departing from the real scope of the invention.

Having thus described my invention, what I claim as new and desire to secure by Letters Patent of the United States is:

1. A machine of the character described, having in combination, means for operating on lifts or the like, a support along which the lifts travel after being operated upon by said means, a rotary carrier adjacent said support, and a series of clamps on said carrier successively operative to take the lifts away from said support.

2. A machine of the character described, having in combination, means for operating on lifts or the like, a support along which the lifts travel after being operated upon by said means, a magazine, transferring means operative to take the lifts from said support and deliver them to said magazine, and mechanism for continuously rotating said transferring means in one direction.

3. A machine of the character described, having in combination, means for skiving lifts or the like, a support along which the skived lifts travel, a magazine, and transferring mechanism located between said sup-

port and magazine operative to pick up lifts from the support and deliver them to said magazine in stack formation.

4. A machine of the character described
5 having, in combination, means for operating upon lifts or the like, a magazine constructed to receive lifts in stack formation, and a rotary transferrer operative to grasp each lift after it has been operated upon by
10 said means and introduce it into the magazine by a movement substantially in the direction of the length of the magazine and to pile them in stacked relation one against another therein.
- 15 5. A machine of the character described, having in combination, means for operating on lifts or the like, a support along which the lifts travel in series after being operated upon by said means, a transferrer operative
20 to take the lifts away from said support, and advancing means operative at a point beyond the operating means to engage the foremost lift of the series on said support and move it into the path of said transferrer.

- 25 6. A machine of the character described, having in combination, means for operating on lifts or the like, a support along which the lifts travel in series after being operated upon by said means, a rotary transferrer operative to take the lifts away from said support, and a reciprocating pusher arranged to separate lifts on the support and separately deliver them into the grasp of
35 said transferrer.

- 30 7. A machine of the character described, having in combination, means for operating on lifts or the like, and mechanism including a transferrer rotating continuously in
40 one direction operative to take the lifts away from said means.

- 45 8. A machine of the character described, having in combination, means for operating on lifts or the like, a magazine for receiving the lifts after they have been operated upon, mechanism for delivering the lifts from said means to said magazine in stack formation, and mechanism including a controlling device positioned for engagement with each
50 lift as it is stacked in the magazine operative automatically to interrupt the operation of the machine upon the failure of the delivering mechanism to deliver a lift to the magazine.

- 55 9. A machine for operating on lifts or the like, comprising, in combination, a skiving mechanism, means for feeding the lifts one at a time to said mechanism, and means for picking up the lifts bodily and transferring them from said mechanism automatically and stacking them.

- 60 10. A machine for operating on lifts or the like, comprising, in combination, a skiving mechanism, a magazine for the lifts,

means for feeding the lifts from said magazine to said mechanism, said means being constructed and arranged to insure the feeding of one lift only at a time, a support along which the lifts travel away from said skiving mechanism, a second magazine for the lifts, and a rotary transferrer operative to take the lifts from said support and deliver them to said second magazine.

11. A machine of the character described, having in combination, means for operating on lifts or the like, a magazine, mechanism for transferring the lifts to said magazine comprising a rotary carrier having a plurality of pairs of grippers, each pair being operative to grasp a lift, and means for moving the pairs of grippers relatively to the carrier to place lifts in the magazine.

12. A machine of the character described, having in combination, means for operating on lifts or the like, and mechanism for transferring the lifts with reference to said operating means comprising a rotary carrier, a plurality of pairs of pivoted grippers mounted on said carrier, each pair being operative to grasp a lift between them, and cam means for moving either gripper of each pair independently of its companion gripper.

13. A machine of the character described, having in combination, means for operating on lifts or the like and mechanism for transferring the lifts with reference to said operating means comprising a carrier movable about an axis, a pivoted gripper mounted on said carrier, cam means for controlling the motion of said gripper about its pivot, a second pivoted gripper mounted adjacent to the first gripper and coöperating therewith to grasp a lift, a spring tending to hold said grippers closed, and means for swinging the second gripper on its pivot against the action of said spring.

14. A machine of the character described, having in combination, means for operating on lifts or the like and mechanism for transferring the lifts with reference to said operating means comprising a carrier, a pair of grippers mounted on said carrier and operative to grasp a lift between them, a magazine in to which said grippers carry the lift, and operating means for said grippers arranged to move them in substantially the plane of the lift after they have deposited it in the magazine to draw them off the lift so deposited.

15. A machine of the character described, having in combination, means for operating on lifts or the like, a support beyond said means over which the lifts are moved after being operated upon, means for advancing the lifts flatwise along said support, and means for guiding the lifts in their travel over said support including devices

arranged to engage yieldingly the opposite marginal portions of the lifts.

16. A machine of the character described, having in combination, means for operating 5 on lifts or the like, a support along which the lifts travel away from said means, guides positioned at opposite sides of said support constructed to overlie the opposite marginal portions of the lifts as they move along 10 said support, and means for lifting said lifts off said support, said guides having pivoted portions enabling them to swing away from said support with each lift until the lift moves out of contact with them.

15. 17. A machine for operating on lifts or the like, having in combination, a pair of rolls between which the lifts are fed, a support along which the lifts travel away from 20 said rolls, and a presser device operative to hold the lifts against said support and mounted for yielding movement both around the axis of one of said rolls and toward and from said support.

18. A machine for operating on lifts or 25 the like, having in combination, a pair of rolls between which the lifts are fed, a support along which the lifts travel away from said rolls, a presser plate operative to hold the lifts against said support, supporting 30 means for said plate operative to enable the forward end of the plate to move around the axis of one of said rolls and the rearward end of the plate to move toward and from said support, and spring means acting to 35 press said plate toward said support.

19. A machine for operating on lifts or the like, having in combination, a pair of rolls between which the lifts are fed, a support along which the lifts travel away from 40 said rolls, a presser plate operative to hold the lifts against said support, a supporting device to which the forward end of said plate is pivoted mounted for swinging movement about the axis of one of said rolls to- 45 ward or from said support, additional supporting means for the rear end of said plate, and spring means acting to press both ends of said plate toward said support.

20. A feed mechanism having, in combi- 50 nation, means for holding a stack of lifts or the like, said means being constructed to permit the forward margin of the first lift to project in front of the second lift, a stop operative to engage the forward edge of the first lift and movable transversely across said edge toward the adjacent lifts in said stack and tending to push the first lift backwardly while in engagement with said edge, and including means operating on the mar- 55 gin of the first lift during said movement to prevent said margin from being displaced by the engagement therewith of said stop, and means for feeding the first lift forward while said stop retains the second lift.

21. A feed mechanism having, in combina- 65 tion, means for holding a stack of lifts or the like, said means being constructed to permit the forward margin of the first lift to project in front of the second lift and including a support against which the first lift 70 rests, a stop comprising a member operative to engage said lift and movable automatically into a variable position determined by the thickness of the first lift and having means operative to press the forward 75 margin of the first lift against said support while said movement is being effected, and means for feeding the first lift forward while said stop retains the second lift.

22. A feed mechanism having, in combi- 80 nation, means for holding a stack of lifts or the like, said means being constructed to permit the forward margin of the first lift to project in front of the second lift and including a support against which the first 85 lift rests, a stop comprising a member movable into the angular space between the margin of the first lift and the edge of the second lift and having means operative to press the margin of the first lift adjacent to said 90 member against said support while said movement is taking place, and means for feeding forward the first lift while said stop retains the second lift.

23. A feed mechanism having, in combi- 95 nation, means for holding a stack of lifts or the like, said means being constructed to permit the forward margin of the first lift to project in front of the second lift, a 100 feeder operative to advance the first lift, a stop member bearing against and movable across the forward edge of the first lift toward the second lift, and means operative to resist any tendency of the margin of the first lift to move with said member. 105

24. A feed mechanism having, in combi- 110 nation, means for holding a stack of lifts or the like, said means being constructed to permit the forward margin of the first lift to project in front of the second lift, a stop finger, means for moving said finger across the forward edge of the first lift to a point in front of the adjacent lifts in said stack, means acting yieldingly on said finger during said movement to cause it to tend to 115 push the first lift backwardly, means operative to prevent the margin of the first lift from moving with said finger, and means for advancing the first lift past said finger while the finger engages the second lift and 120 retains it.

25. A feed mechanism having, in combi- 125 nation, means for holding a stack of lifts or the like, said means being constructed to permit the forward margin of the first lift to project in front of the second lift, a stop finger, means for moving said finger across the forward edge of the first lift to a point

- in front of the adjacent lifts in said stack, means acting during said movement to press said finger backward yieldingly toward said stack, a presser foot mounted to bear on the 5 margin of the first lift adjacent to said finger, means for pressing said presser foot against said margin while said finger is moving across the edge of the first lift, and means for advancing the first lift past said 10 finger and presser foot after the finger has moved out of engagement with the edge of the first lift and while it retains the second lift.
26. A feed mechanism having, in combination, means for holding a stack of lifts or the like, said means being constructed to permit the forward margin of the first lift to project in front of the second lift and including a support against which the first 15 lift rests, means for expelling the first lift from the stack, and a stop for retaining the second lift while the first lift is being expelled, said stop comprising a finger, a presser foot, means for advancing and re- 20 tracting said finger and presser foot operative to move the finger across the forward edge of the first lift away from said support while the presser foot holds the margin of the first lift against said support, and means 25 for urging said finger yieldingly backward during its movement across said edge whereby it will be moved into the angular space between the margin of the first lift and the forward edge of the second lift as soon as 30 it moves out of engagement with the edge of the first lift.
27. A feed mechanism having, in combination, means for holding a stack of lifts or the like, said means being constructed to permit the forward margin of the first lift to 35 project in front of the second lift and including a support against which the first lift rests, means for expelling the first lift from the stack, and a stop for retaining the second lift while the first lift is being expelled; said stop comprising a finger, a presser foot, and operating means for said finger and presser foot constructed and arranged to move them both simultaneously 40 and relatively to cause the finger to move across the forward edge of the first lift into the angular space between the margin of the first lift and the forward edge of the second lift while the presser foot holds the 45 margin of the first lift against said support, then to retract said finger and advance it again yieldingly into contact with the first lift and thereafter to retract said presser foot.
- 50 28. A skiving mechanism, having in combination, two rolls mounted to bear on opposite faces of the work, a knife projecting between said rolls, a pivoted yoke supporting one of said rolls for bodily movement 55 into an inoperative position relatively to the other roll to afford free access to the space between said rolls, and means for automatically locking said roll when the yoke is returned to its operative position.
29. A machine of the character described, having, in combination, means for operating upon lifts or the like, mechanism for feeding lifts to said means in an intermittent succession, a support across which lifts are pushed by the movement of the following lift, devices operative automatically to take lifts away from said support, and mechanism for stopping the operation of the machine controlled by an interruption of the continuity of the succession of lifts to said devices. 65
30. A machine of the character described, having, in combination, a skiving knife, a feed roll and positioning roll for supporting a lift or the like while it is being skived, means to intermittently advance lifts to said 70 rolls, a transfeerer for receiving skived lifts and delivering them to a magazine, and automatically controlled means for stopping the machine upon an interruption of the continuity of the passage of the lifts to the 75 magazine.
31. A machine of the character described, having, in combination, a yieldingly supported feed roll, a coöperating positioning roll, a skiving knife between the rolls, said 80 positioning roll being movable between two fixed positions with relation to the feed roll, and means to normally hold the positioning roll in the position nearest the feed roll whereby a thin blank which may not be 85 skived will be fed.
32. A machine of the character described, having, in combination, a yieldingly supported feed roll, a coöperating positioning roll, a skiving knife between the rolls, and 90 means to yieldingly press the positioning roll toward the feed roll to assist in feeding the work.
33. A machine of the character described, having in combination, a feed roll yieldingly mounted in the machine frame, a co-operating positioning roll, a skiving knife between the rolls, a yoke for supporting said 95 positioning roll pivotally mounted for movement toward and from the feed roll, and a connection between the yoke and machine frame by which the positioning roll may be supported in a relatively fixed position with 100 relation to the skiving knife, said connection permitting a movement of the positioning roll relatively to the feed roll by reason of the passage of work between the rolls.
34. A machine of the character described, having, in combination, a feed roll yieldingly mounted in the machine frame, a co-operating positioning roll, a skiving knife mounted between the rolls, a movably mounted yoke for said positioning roll, an adjust- 110
- 115
- 120
- 125

- able connection between the yoke and machine frame by which the positioning roll may be supported in a relatively fixed position with relation to the skiving knife, said 5 connection permitting a movement of the positioning roll relatively to the feed roll, and means to yieldingly press the positioning roll toward the feed roll to assist in feeding the work.
- 10 35. A machine of the character described, having, in combination, lift skiving mechanism, means for feeding lifts to said mechanism, a magazine, and continuously rotating means operating to stack the skived lifts in 15 the magazine.
36. A machine of the character described, having, in combination, a lift magazine, co-operating positioning and feeding rolls, a skiving knife between the rolls, means for 20 feeding lifts from said magazine to the rolls, a receiving magazine, a rotatably mounted transferring means for taking lifts released by said rolls and delivering them to the receiving magazine, and means for continuously 25 rotating said transferring means.
37. A machine of the character described, having, in combination, lift skiving mechanism, a magazine to receive the skived lifts, means for stacking lifts in the magazine, and 30 a support extending between the skiving mechanism and the stacking means over which lifts in series are pushed to the stacking means by the advance of lifts from the skiving mechanism.
- 35 38. A machine of the character described, having, in combination, means for operating upon lifts or the like, a magazine, a lift support, and arranged between said means and magazine arranged in said order to which 40 the lifts are delivered after being operated upon, a carrier rotatably mounted between the magazine and the support, a plurality of devices on said carrier for removing lifts from the support and delivering them successively to said magazine in stack formation, 45 and means for rotating the carrier.
39. A machine of the character described, having, in combination, means for operating on lifts or the like, a magazine, a lift support, and arranged between said means and magazine arranged in said order to which the lifts are delivered after being operated upon, a carrier rotatably mounted between the magazine and the support, a plurality of 50 devices on said carrier for removing lifts from the support and delivering them successively to said magazine, means for rotating the carrier, and means on the magazine for removing the lifts from said devices.
- 60 40. A machine of the character described, having, in combination, a table, a skiving knife, co-operating feeding and positioning rolls, a support for skived lifts, means for automatically feeding lifts from the table to the rolls, means for rotating the rolls, and a yielding presser plate opposite the support to hold the skived lifts against the support whereby the feed rolls will move lifts in series across the support.
41. A machine of the character described 70 having, in combination, a lift-skiving mechanism including feed rolls and a skiving knife, means for supporting a stack of lifts, a pusher for advancing an end lift of the stack to said feed rolls and knife, a magazine 75 to receive the skived lifts in stack formation, a device at one end of the magazine for engaging each skived lift and pushing it into the magazine flatwise against the stack, and means to guide the skived lifts to 80 said device.
42. A machine of the character described having, in combination, a lift skiving mechanism, automatic means for successively feeding lifts to said mechanism, a magazine beyond 85 said mechanism arranged to receive the skived lifts in a horizontal stack, rotary means for successively pressing the skived lifts into one end of said stack, and means for guiding the skived lifts from said mechanism to a position to be engaged by said rotary means.
43. In a skiving machine of the type in which a skiving knife is arranged opposite the bite of a pair of feed rolls, the combination 90 with said rolls of a guide to which the skived lifts are delivered by said rolls, a magazine beyond the guide to receive the skived lifts in a horizontal stack, and a rotary device intermediate the guide and receiving magazine constructed and arranged to press the skived lifts successively into the end of the magazine and pile them in stacked relation one against another therein.
44. In a skiving machine of the type in 105 which the skiving knife is arranged opposite the bite of a pair of rotary rolls and blanks are fed to said rolls from a delivery magazine at the side opposite said knife, the combination with said devices of a receiving 110 magazine on the knife side of the rolls, a blank transerrer mounted on a pivot extending parallel to the axes of said rolls located between the skiving mechanism and the receiving magazine, a guide leading to 115 the transerrer to which the skived blanks are delivered by said feed rolls, and means to rotate said transerrer on its pivot to engage a lift from said guide and deliver it to the receiving magazine.
45. A machine of the character described 120 having, in combination, lift skiving mechanism, a guide to which the skived lifts are delivered as they emerge from said skiving mechanism, a receiving magazine, a device for pressing the skived lifts successively into said magazine, and automatically controlled means to interrupt the operation of 125

the machine upon an interruption of the continuity of the passage of the lifts to said device.

46. A machine of the character described having, in combination, means for skiving lifts or the like, a receiving magazine, a yieldable latch for retaining the stack of lifts within the magazine, lift transferring mechanism operative to engage the skived lifts and press them into said magazine past said latch, mechanism tending periodically to stop the operation of the machine, and means operated by the movement of said latch when a lift is pressed into the magazine for nullifying the action of said stop mechanism.

47. A machine of the character described having, in combination, means for operating on lifts or the like, a magazine constructed to receive the lifts in stack formation, a yieldable latch for retaining the stack of lifts within the magazine, and a transferrer operating to engage each lift in a position outside the magazine after it has been operated upon by said means and deposit it within the magazine behind said latch in face to face relation with the lift previously deposited.

48. A machine of the character described having, in combination, means for skiving lifts or the like, a magazine, a yieldable latch for retaining a stack of lifts within the magazine, a rotary transferrer for receiving each lift and pressing it into said magazine past said latch, and means to guide the skived lifts from the skiving means to said transferrer.

49. A stacking mechanism for blanks having, in combination, a magazine for the blanks, and a single means for gripping the blanks and piling them in stacked relation one against another in the magazine.

50. A stacking mechanism for blanks having, in combination, a magazine for the blanks, a pair of jaws between which the blanks may be delivered, and means for operating the jaws to grip the blanks and pile them in stacked relation one against another in the magazine.

51. A stacking mechanism for blanks having, in combination, a pair of jaws between which each blank may be delivered, a magazine for a stack of blanks, and means for causing the jaws to grip each blank delivered to them, to add the blank to the stack and to push the stack along in the magazine.

52. The combination with a machine for operating upon blanks, of a magazine for

the blanks, a movable transferrer, and means for causing the transferrer to grip 60 the blanks one by one and pile them in stacked relation one against another in the magazine.

53. The combination with a machine for acting upon blanks, of a magazine for the blanks, a pair of jaws between which the blanks are delivered, and means for operating the jaws to grip the blanks and pile them in stacked relation one against another in the magazine. 70

54. The combination with a machine for acting upon blanks, of a magazine for a stack of blanks, a transferrer comprising a pair of jaws, means for directing the blanks one by one from the machine to the transferrer, and means for causing the jaws to grip each blank, to move the stack along and to release the blank in parallel relation to the preceding blank. 75

55. The combination with a machine for acting upon blanks, of a magazine for the blanks, and a transferrer for stacking the blanks in the magazine, said transferrer comprising a pair of jaws, means for moving the jaws from a position in which they 85 are located to receive a blank from the machine to a position in contact with the stack in the magazine, and means for opening and closing said jaws.

56. The combination with a machine for acting upon blanks, of a magazine for the blanks, a transferrer, means for receiving the blanks as they are delivered by the machine and for transferring them to the transferrer, and means for operating the 95 transferrer to stack the blanks in the magazine.

57. A stacking mechanism for blanks having, in combination, means for supporting a stack of blanks, a latch for engaging that 100 end of the stack to which the blanks are to be added, a pair of jaws to which a blank may be delivered, and means for operating the jaws to grip a blank and force it past the latch. 105

58. Stacking mechanism for blanks comprising a blank receiving magazine having a slotted wall at its receiving end constructed to hold the blanks in a stack on edge, a blank feeding device outside the 110 magazine adjacent said slotted wall constructed and arranged to feed blanks forward by entering through the slot in said wall, and means for actuating said device.

ERASTUS E. WINKLEY.
